US0D1006000S

(12) **United States Design Patent** (10) Patent No.: **US D1,006,000 S**
(45) Date of Patent: ** Nov. 28, 2023

(54) **WIRELESS ADAPTER FOR CAR**

(71) Applicant: **Dongguan Youweite Electronics Co., Ltd.**, Dongguan (CN)

(72) Inventor: **Ruyan Huang**, Zhangzhou (CN)

(73) Assignee: **Dongguan Youweite Electronics Co., Ltd.**, Dongguan (CN)

(**) Term: **15 Years**

(21) Appl. No.: **29/900,545**

(22) Filed: **Aug. 22, 2023**

(51) LOC (14) Cl. **14-03**

(52) U.S. Cl.

USPC **D14/240; D14/433; D14/435.1**

(58) **Field of Classification Search**

USPC D14/240, 356, 435, 435.1, 480.5, 484.1; D13/103, 107, 108, 118-121, 123, 133, D13/145-147, 149, 151, 153, 154, 173, D13/184, 199

CPC H01R 9/00; H01R 12/00; H01R 12/72; H01R 13/00

(57) **CLAIM**

The ornamental design for a wireless adapter for car, as shown and described.

DESCRIPTION

FIG. 1 is a top, front and right side perspective view of a wireless adapter for car showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines showing the wireless adapter for car that form no part of the claimed design.

1 Claim, 8 Drawing Sheets
